US0D1045754S

(12) **United States Design Patent** (10) Patent No.: **US D1,045,754 S**
(45) Date of Patent: ** Oct. 8, 2024

(54) **BIKE CARRIER**

(71) Applicant: **NINGBO CHENFAN AUTO ACCESSORIES CO., LTD**, Zhejiang (CN)

(72) Inventor: **Shouguang Huo**, Zhejiang (CN)

(73) Assignee: **NINGBO CHENFAN AUTO ACCESSORIES CO., LTD**, Zhejiang (CN)

(**) Term: **15 Years**

(21) Appl. No.: **29/863,048**

(22) Filed: **Dec. 15, 2022**

(30) **Foreign Application Priority Data**

Jun. 29, 2022 (CN) 202230404374.5

(51) **LOC (14) Cl.** **12-16**

(52) **U.S. Cl.**

USPC **D12/408**

(58) **Field of Classification Search**

USPC D12/406-408, 412, 414, 115
CPC .. B60R 9/06; B60R 9/10; B60R 9/045; B60R 9/048
